UNITED STATES PATENT OFFICE.

JOHN FRANK KAMINSKY, OF MILDRED, PENNSYLVANIA.

RAILWAY-TIE.

No. 838,255.

Specification of Letters Patent.

Patented Dec. 11, 1906.

Application filed September 25, 1906. Serial No. 338,107.

To all whom it may concern:

Be it known that I, JOHN FRANK KAMINSKY, a citizen of the United States, residing at Mildred, in the county of Sullivan and 5 State of Pennsylvania, have invented certain new and useful Improvements in Railway-Ties, of which the following is a specification, reference being had to the accompanying drawings.

10 My invention relates to improvements in railway-ties; and the object of my invention is to provide a tie which will be durable, comparatively cheap in construction, and easily handled.

15 In the drawings illustrating the principle of my invention and the best mode now known to me of applying that principle, Figure 1 is a perspective view of my new railroad-tie. Fig. 2 is a central longitudinal sectional view, 20 and Fig. 3 is a sectional view on line A A of Fig. 2.

The outer casing *a* is made up of sheet-iron, and its edges meet along the joint *b*, the overlapping edges being riveted, Fig. 1. 25 Centrally disposed in this casing is a block of concrete *c*, and the ends of the tie are also formed of concrete blocks *d*, between which and the central block of concrete *c* are placed blocks of wood *e*, to which the rails are 30 spiked. The rail-bed of the sheet-iron casing *a* is formed with holes *f*, through which

spikes are driven upon the outside of the rails, and with holes *g*, through which spikes are driven upon the inside of the rails, the spikes in both instances entering the wooden 35 blocks *e*, Fig. 3.

The sheet-iron casing *a* is formed with indentations *h*, which serve to hold the concrete securely in place.

In each end of the tie is formed a passage *i*, 40 which enables the workmen to handle the tie with ease.

It is to be noted that the wooden blocks *e* are carefully protected from exposure by means of the casing and the concrete blocks. 45

I claim—

A railway-tie made up of a sheet-metal casing, a block of cementitious material centrally disposed within said casing; end blocks of cementitious material within said casing; 50 and blocks of wood interposed between said cementitious blocks below the rail-bed; said casing being formed with holes for the passage of spikes into said wooden blocks, with holes for the handling of the tie and with indentations to hold the cementitious material securely. 55

JOHN FRANK KAMINSKY.
